UNITED STATES PATENT OFFICE.

JAMES SUTHERLAND WARNER, OF FOREST GATE, ENGLAND.

RADIAL RAILWAY AND TRAMWAY TRUCK.

No. 819,189.

Specification of Letters Patent.

Patented May 1, 1906.

Application filed November 2, 1905. Serial No. 285,647.

To all whom it may concern:

Be it known that I, JAMES SUTHERLAND WARNER, A. M. I. Mech. E., a subject of the King of Great Britain, residing at Glen Deep, 5 Disraeli Road, Forest Gate, Essex, England, have invented new and useful Improvements in Radial Railway and Tramway Trucks, of which the following is a specification.

My invention relates to railway and tramway trucks of the kind known as "radial" axle trucks or vehicles, and has for its object to provide improved means for connecting the axles and vehicle in order to reduce the friction between the parts when the wheels move relatively with the vehicle-frame and at the same time to cushion the movement.

In carrying out my invention as applied to a tramway radial truck of the type wherein the motor suspension is a central pivotal point about which the motor, axle, axle-boxes, and wheels may rotate in a horizontal plane I connect the truck-frame to the axle-boxes by suspension-links so arranged that they connect the journals and the truck-frame and control their relative movement, their swing being approximately through an arc having at its center the aforesaid pivotal point. When the vehicle is running in a straight line, the links are advantageously 30 vertical, although they may be arranged so that they are inclined toward or away from each other.

In the accompanying drawings, Figure 1 is a sectional elevation of a portion of a radial truck having the improvements applied thereto. Fig. 2 is a plan view of the same. Fig. 3 is a section on the line 3 3, Fig. 1. Fig. 4 is a section on the line 4 4, Fig. 1. Fig. 5 is a view similar to Fig. 1, illustrating a modification. Fig. 6 is a plan view thereof, and Figs. 7 and 8 are a side view and a plan view, respectively, illustrating a modified form of suspension.

Referring first to the construction illustrated in Figs. 1 to 4, *a* is the upper part of the truck-frame, upon which the body of the vehicle rests, and *b* is the lower part of the said frame, this frame *b* being formed with the yokes *c c*, within which extend the axle-boxes *d d*, carrying the axle *e* and mounted in the subtruck-frame *f*, which is pivoted at the point *g* in the truck-frame *a b*.

Each of the axle-boxes *d* has placed upon its upper side and extending across the same 55 a plate *h*, the said plate *h* being provided at

each end with a horn or bearing *i*, projecting laterally from the axle-box and at such an inclination thereto that their longitudinal axes when continued would intersect at the aforesaid pivotal center *g*, as clearly shown in Fig. 60 2. Upon each of the bearings or horns *i* there is freely suspended a link *j*, having at its lower end a head *k*, supporting a washer *l*, upon which rests the lower end of a spiral spring *m*. The upper ends of these springs 65 support the aforementioned frame *b*, so that the weight of the vehicle is transmitted from the truck through the springs *m m* and links *j* to the axle-boxes *d* of the vehicle. With this construction it will be seen that when the 70 vehicle is entering and running on a curved track the wheels *n* can at first move laterally relatively with the frame *b* with a minimum of friction, owing to the link suspension, the upper ends of the links moving through 75 circular arcs around the point *g* as a center and the links assuming an inclination which varies with the radius of curvature of the track.

In practice it is advantageous to make use 80 of flexible links, and this may be effected either by jointing the same, as shown at *o o*, Fig. 1, or by employing chain-links. Furthermore, additional washers *l* may be provided to raise the height of the truck-frame, 85 this being sometimes required—as, for instance, when wheels are worn down or when a pair of new wheels at one end of the vehicle is used with a pair of worn wheels at the other end thereof. 90

In the construction just described each axle-box *d* is secured to the subtruck-frame *f* by means of the bolts *p p*, and this arrangement is open to the disadvantages that the bolts *p p* are placed in a position which is 95 difficult of access and that the links *j j* cannot be attached and detached or the boxes *d d* removed with facility. To overcome these disadvantages, I may employ the construction shown in Figs. 5 and 6. In this arrangement the subtruck-frame *f* is cast or made in one piece with the plates *h*, the under side of each of the said plates *h* and the top of each axle-box *d* being made with transverse ridges *q q*, so that the two parts lock together when their plate is placed in position. This allows any box *d* to be instantly drawn off for inspection after the frames *b* and *f* have been slightly raised. 105

To enable the links *j* to be placed in pos- 110

tion with facility, the plate *h* is provided with recesses *r r* for the introduction of the heads of the links and with holes *s*, which are accessible from lateral recesses *t t* to permit of pins *u u* being passed through the eyes of the links *j*. These pins are retained in place when the plate *h* is placed in position upon the axle-box *d*, as will be obvious on referring to Fig. 6.

- 10 In the constructions above described I have illustrated the employment of spiral or helical springs *m* between the links and the frame *b*; but it will be obvious that other forms of spring, such as semi-elliptical springs, may be employed. Figs. 7 and 8 illustrate an arrangement of this kind. The links in this construction are formed in one piece, as the stirrup *v*, which is placed diagonally across the top of the axle-box *d*, its two 15 lower ends passing through a plate *w*, which is supported upon nuts *x* upon the said lower ends and serves to itself support the semi-elliptical spring *y*, extending between the two limbs of the stirrup *v*. As when a vehicle is 20 stopped on a sharp curve the body would float inward upon the links and by carrying the pivots *g* also inward tend to straighten out the wheels and lock the flanges of the latter against the rails, I advantageously trans- 25 30 versely elongate the hole in the truck-frame through which the pivot *g* passes, as shown at *g'*, Fig. 2. The elongated hole is made of such a length that it extends on each side of the center a distance equal to one-fourth of 35 the extreme swing of the subtruck-frame measured laterally.

Having now particularly described and ascertained the nature of my said invention and in what manner the same is to be performed, I declare that what I claim is—

- 40 1. In a radial railway and tramway truck, the combination with a vehicle-supporting frame, of a subtruck-frame provided with a pin adapted to engage with a slot in said ve- 45 hicle-supporting frame, axle-boxes connected to said subtruck-frame, an axle mounted in said axle-boxes, wheels mounted on said axle and connections between said axle-boxes and said supporting-frame whereby said axle 50 and wheels may move transversely and longitudinally of the vehicle, substantially as described.

2. In a radial railway or tramway truck, the combination with a vehicle-supporting frame, of a lower frame yieldingly supporting said vehicle-supporting frame, an axle, wheels mounted thereon and connections between said axle and said lower frame whereby said axle and wheels may move transversely and

longitudinally of the vehicle, substantially as described.

3. In a radial or tramway truck, the combination with a vehicle-supporting frame, of a lower frame yieldingly supporting said vehicle-supporting frame, axle-boxes, an axle 65 mounted therein, wheels mounted on said axles, and links connecting said axle-boxes and said lower frame whereby said axles and wheels may move transversely and longitudinally of the vehicle, substantially as de- 70 scribed.

4. In a radial or tramway truck, the combination with a vehicle-supporting frame, of a lower frame yieldingly supporting said vehicle-supporting frame, axle-boxes, an axle 75 mounted therein, wheels mounted on said axles, links connected to said axle-boxes passing through orifices in said lower frame, yielding connections between said links and said frame whereby said axle and wheels may move transversely and longitudinally of the vehicle, substantially as described. 80

5. In a radial railway or tramway truck, the combination with the axle-boxes of stirrups which straddle the same at an inclination to the longitudinal axis thereof and support springs carrying the truck-frame, sub- 85 stantially as described.

6. In a radial railway or tramway truck, the combination with the axle-boxes of plates 90 having horns or pivots for supporting links inclined to and carrying the truck-frame through the medium of springs, substantially as described.

7. In a radial railway or tramway truck, 95 the combination with the axle-boxes of plates integral with the pivoted subtruck-frame and adapted to rest upon the axle-boxes, the said plates being recessed to receive the heads of links pivoted thereto and carrying the 100 truck-frame through the medium of springs, substantially as described.

8. In a radial railway and tramway truck, the combination with a vehicle-supporting frame, of a lower frame yieldingly supporting the same, axle-boxes, plates on said axle-boxes and provided with pivot-pins having their longitudinal axes extending toward the same point, links fulcrumed on said pins and extending through orifices in said lower frame and yielding connections between said links and said frame, substantially as de- 105 scribed.
